UNITED STATES PATENT OFFICE.

JAMES COOPER, OF YOUNGSTOWN, OHIO.

REGENERATOR FOR HEATING-FURNACES.

1,124,593.

Specification of Letters Patent.

Patented Jan. 12, 1915.

Application filed October 14, 1913. Serial No. 795,141.

To all whom it may concern:

Be it known that I, JAMES COOPER, a citizen of the United States, and resident at Youngstown, in the county of Mahoning and 5 State of Ohio, have invented certain new and useful Improvements in Regenerators for Heating-Furnaces, of which the following is a specification.

My invention relates to the construction of 10 regenerative heating furnaces, and more particularly relates to the construction and arrangement of regenerators of the double surface type, largely used with regenerative heating furnaces.

15 In one form of regenerative heating furnace of the double surface regenerator type which is largely used, the regenerator chamber is positioned immediately beneath the floor of the furnace adjacent to one of its 20 ends. The chamber is provided with a series of regenerator pipes or conduits which have open ends opening without the regenerator chamber. In some cases the products of combustion are led through these pipes in 25 their passage from the furnace to the furnace stack and simultaneously therewith the air or unburned hydrocarbon gases, or both, are caused to pass through the regenerator chamber and contact with the surfaces of the 30 regenerator pipes or conduits. In other cases the operation is reversed and the air is led through the regenerator pipes while the highly heated burned gases or products of combustion are caused to pass through the 35 regenerator chamber and by contact therewith heat the pipes or conduits to a high temperature and the heated tubes heat the air or unburned gases contacting therewith in its passage to the air and gas inlets on 40 the heating furnace. In such manner the waste heat of the burned gases is caused to highly heat, through the walls of the pipes or conduits, the incoming air or gases during its or their passage through the regener- 45 ators of the furnace.

It is to be understood that the air and unburned gases are heated separately, when both are being heated, separate regenerator chambers being provided therefor.

50 The pipes or conduits used in forming the regenerators burn out and leak and become otherwise impaired, so that after extended use the defective pipes must be removed and repaired or replaced by other pipes or conduits.

In any of the constructions heretofore

known to me the renewal and replacement of the pipes or conduits has necessitated practically demolishing the end of a furnace below which the regenerator chamber containing the pipes is located, that is, the furnace roof and the skids or equivalent bottom of the furnace immediately above the chamber containing the regenerator pipes must be removed. The necessity of dismantling or 60 removing such portions of the furnace preparatory to repairing the regenerators has occasioned long delays in the operation of the furnace and has been the cause of considerable expense in material and labor. 65

One object of my invention is to provide a regenerative furnace having the regenerator chamber and pipes therefor constructed and arranged to permit the removal and replacement of the pipes or conduits within a 70 minimum time and at comparatively slight expense.

Another object of my invention is to provide a regenerator construction having novel means whereby the removal and replacement 80 of the regenerators within the regenerator chamber is facilitated, the time required in making such removals and replacements is lessened, and the expense of operating the furnace is thereby greatly reduced. 85

The invention will be more clearly understood by reference to the accompanying drawings forming part of this specification in which—

Figure 1 is a longitudinal vertical section 90 through a heating furnace showing the regenerator construction forming this invention. Fig. 2 is a plan showing a detail of one of the dividing plates whereby the pipes or conduits are held in spaced apart relation. 95 Fig. 3 is a sectional plan, taken on the line III—III of Fig. 1, showing the relative position of the regenerator pipes as located within the regenerator chamber of the furnace. 100

In the drawings the numeral 10 designates the roof of a furnace having an end wall 11 and having inclined water cooled skids 12 located at separated intervals in the width of the furnace which are positioned at the 105 metal receiving end of the furnace to extend above and across the regenerator chamber of the furnace. The spaces 23 between the skids 12 form passages by which communication is afforded between the furnace chamber 110 24 and the top of the regenerator chamber and at the bottom of the regenerator

chamber is a series of openings 25 leading therefrom into the waste gas flue 14 which is connected to a furnace stack (not shown).

Positioned to extend lengthwise vertically within the regenerator chamber is a series of regenerator pipes or conduits 16, which are held at spaced apart intervals within the regenerator chamber by means of top plates 18 and bottom plates 19. The side walls 26 of the regenerator chamber and the partition walls 27 therein which are located in line with and immediately below the skids 12 have ledges 20^a (see Figs. 1 and 3) at intervals in the height thereof arranged to support the series of spreader plates or separators 20 which, when placed in position within the regenerator chambers, form, with the top plate 18 and bottom plate 19, horizontal division walls or baffles for directing the flow of air through the compartments 28, 29, 30, 31 and 32 of the regenerator chamber and around the pipes within the regenerator chamber.

The top and bottom end of each of the pipes 16 is provided with an open ended cap 17, the ends of the pipes extending into recesses within the caps. The caps 17 on the bottom end of the pipes have a projecting portion extending into the opening in the bottom plate 19 and the caps on the upper end of the pipes are also provided with an annular projection which extends into similar openings in the top plate 18. The plates or baffles 20 have semi-circular or arc-shaped recesses 21 therein of a size somewhat larger than the diameter of the pipes 16, to form annular openings through which the air passes from one to the next compartment of the regenerator chamber. These baffles 20 also are provided with flanged side edges 22 offset in such manner as to overlap and partially interlock with the side edge of an adjacent plate when in position within the regenerator chamber, and the ends of the plates 20 rest on ledges 20^a provided on the faces of the adjacent walls 26 and are supported thereby. It will be seen from this construction that when the regenerator pipes and caps therefor are placed in position in the regenerator chamber with the plates or baffles in engagement therewith a rigid structure is formed.

In the operation of furnaces having regenerators constructed in accordance with my invention, the parts are preferably assembled as shown. The products of combustion pass out of the furnace chamber 24 into the upper compartment 28 of the regenerator chamber and then pass downwardly through the openings in the series of pipes 16 and emerge below the bottom plate 19 into the open space forming the compartment 33 at the bottom of the regenerator chamber, passing outwardly therefrom through the openings 25 into the stack

flue 14 by which the burned gases are led to the stack (not shown). Simultaneously therewith the air or, when gas is to be heated, the unburned hydrocarbon gases are led through the flue 13 and passing through the series of openings 34 enter the compartment 32 formed between the lower row of baffle plates 20 and the bottom plate 19. The air passes therefrom through the annular openings formed by and between the pipes 16 and the edges of the openings in the lower set of baffle plates 20 into the next compartment 31 formed by the lowermost and next row of baffle plates 20 and, successively, through the annular openings in the baffle plates into the next two compartments 30 and 29 formed in the regenerator chamber between the baffle plates 20 and between the top row of the baffle plates 20 and the top plate 18 then passing out of the openings 35 into the flue 15 by which the heated air or gas, as the case may be, is led to the opposite end of the furnace through which end the heated air or gas is introduced into the furnace where it is burned. When, after extended use or for other reasons, the regenerator pipes 16 have become cracked or otherwise damaged and it is necessary to remove and replace one or more of these pipes the operation of the furnace is stopped.

The end wall 11 used to fill the arched opening provided in the end of the furnace is then removed. The necessary number of the plates 20 at the end of the regenerator chamber are then removed and the regenerator pipes in the first row of pipes are lifted vertically until the bottom cap 17 is out of engagement with the bottom plate 19, the caps 17 being conveniently positioned temporarily within the transverse flues 34 as shown by dotted lines in Fig. 1. The pipes 16 in the end row of pipes can then be lowered separately until the top end thereof is clear or out of engagement with the top plate 18 and each pipe can then be moved into the dotted line position shown in Fig. 1 and from this position lifted out of the furnace regenerator chamber. These operations can then be repeated for such of the remaining rows of pipes as need repairs or replacement and in this way the renewal of the regenerator pipes is made a simple matter.

In replacing the pipes within the regenerator chamber a reversal of the steps just described is performed, after which the wall 11 is rebuilt within the opening in the end wall of the furnace and the furnace is again in readiness to be operated.

It is obvious that modifications in the construction shown can be made without departing from my invention.

The burned gases or products of combustion may be caused to pass around the regenerator pipes and the air to be heated pass

through the regenerator pipes, instead of the reverse as illustrated, and other changes may be made within the scope of the appended claims.

5 I claim:

1. In a heating furnace the combination of a heating chamber, a regenerator below the furnace chamber and a passage connecting the bottom of said chamber with the 10 regenerator, said regenerator comprising top and bottom supports, pipes arranged between said supports, and bottom interlocking devices removably engaging said bottom support and said pipes, the parts being held 15 in interlocking engagement by gravity; substantially as described.

2. In a heating furnace the combination of a heating chamber, a regenerator below the furnace chamber and a passage connecting the bottom of said chamber with the 20 regenerator, said regenerator comprising open ended pipes and top and bottom plates, said plates forming means for supporting said pipes in spaced relation, and interlocking caps engaging said pipes at top and bottom whereby said pipes are held in engagement with said plates by gravity; substantially as described.

3. In a heating furnace the combination of 30 a heating chamber, a regenerator and a passage connecting the bottom of said chamber with the regenerator, said regenerator comprising pipes, top and bottom plates having apertures with which said pipes register, and 35 interlocking caps engaging said pipes and said plates, said pipes being held in engagement with said interlocking caps and said plates by gravity; substantially as described.

4. In a heating furnace the combination 40 of a heating chamber, a regenerator and a passage connecting the bottom of said chamber with the regenerator, said regenerator comprising pipes, top and bottom plates having apertures registering with the 45 passage through said pipes, said top and bottom plates being spaced apart a distance greater than the length of said pipes, and an interlocking device provided at the lower end of each pipe and having a separable 50 connection therewith; substantially as described.

5. In a heating furnace the combination 55 of a heating chamber, a regenerator and a passage connecting the bottom of said chamber with the regenerator, said regenerator comprising apertured top and bottom supports, pipes registering with said apertures, and means for removably maintaining said pipes in operative position, said means including caps fitting said pipes and the apertures in said bottom support; substantially as described.

6. In a heating furnace the combination

of a heating chamber, a regenerator and a 65 passage connecting the bottom of said chamber with the regenerator, said regenerator comprising apertured top and bottom supports, pipes located between said supports, said pipes being of a length less than the distance between said supports, and bottom 70 interlocking devices, such devices serving to increase the length of said pipes and provide an interlocking engagement with said support; substantially as described.

7. In a heating furnace the combination 75 of a heating chamber, a double surface regenerator and a passage connecting the bottom of said chamber with the regenerator, said regenerator comprising top and bottom supports, pipes mounted between said supports and removably engaging the same, and intermediate interlocking devices forming caps and serving to maintain said pipes in spaced relation; substantially as described.

8. In a heating furnace the combination 85 of a heating chamber, a regenerator beneath the chamber and a passage connecting the chamber with the regenerator through the bottom of the chamber, said regenerator comprising side and end walls, supports carried by said walls, regenerator pipes mounted between said supports and removably engaging the same whereby said pipes may be displaced and removed from the furnace by first removing the closure in the opening in 90 an end wall thereof; substantially as described.

9. In a heating furnace, a double surface regenerator comprising top and bottom supports, pipes mounted between said supports 100 and removably engaging therewith intermediate interlocking devices forming caps and serving to maintain said pipes in spaced relation and a baffle plate between said top and bottom supports, said baffle plate being 105 made in sections with the joints formed by adjacent side edges of the sections in line with the axial centers of the pipes; substantially as described.

10. In a heating furnace, a double surface 110 regenerator comprising top and bottom supports, pipes mounted between said supports and removably engaging therewith intermediate interlocking devices forming caps and serving to maintain said pipes in spaced relation and a series of baffle plates between said top and bottom supports, said baffle plates being made in sections with the joints formed by adjacent side edges of the sections in line with the axial centers of the 115 pipes; substantially as described.

JAMES COOPER.
